TELEPHONE SYSTEM

William George Patterson, Merton, London,
and Reginald Griffith Dixon, Eltham, London,
England, assignors to Siemens Brothers &
Company Limited, London, England

Application November 9, 1935, Serial No. 48,952
In Great Britain November 14, 1934

3 Claims. (Cl. 179—27)

This invention relates to telephone systems and more particularly to systems in which connections between calling and called subscribers include automatic hunting or selecting switches.

It is usual to arrange that the automatic switches employed in a connection are held under the control of the caller but systems are known in which the release of a connection and the freeing of the line circuits of both subscribers engaged in a connection is effected only after both subscribers have cleared. In a system of this latter type the calling subscriber's line circuit is held engaged unnecessarily should the called subscriber delay clearing.

In the present invention arrangements are provided for maintaining the route over a train of switches employed in a connection until both subscribers have cleared yet allowing that subscriber who has cleared to make and receive calls during the time the route is held by the other subscriber. The arrangements are especially applicable to a system in which a calling line is connected to a common switching apparatus by means of a call finder.

In the arrangements of the invention a signal is transmitted from the point at which the control of a connection is situated, i. e. a feeding bridge circuit, when, after a communication between the two parties to a call has been established, one of them clears, the effect of the signal being to place an engaged marking on all the switches employed in the connection and to prevent their release yet effect the removal of the engaged marking and the release of the cut off relay in the line circuit of the first party to clear. If the switches to be held are non-homing switches the signal has only to bring about the aforesaid engaged marking, the ordinary releasing arrangements operating as usual. If any of the switches over which a connection is established are homing switches the signal must provide for maintaining the switch wipers on the contacts on which they were last used yet allow for the release of the cleared subscriber's cut-off relay and the removal of the engaged marking.

The invention may be applied to a full automatic system or to a semi-automatic system. The invention will be regarded, in the following specification as applied to a system in which a calling line is automatically extended to a cord circuit at an operator's position and to the operator's telephone, and in which the operator upon ascertaining the subscriber's requirement further extends the connection by inserting the cord circuit to which the calling line was extended into

the jack of the wanted line, leaving the apparatus automatically to complete or to refuse to complete the connection in accordance with the free or engaged condition of the wanted line. Clearing of an established connection is effected by the operator in response to a double supervisory signal, though either subscriber's line is freed for further use, either for the initiation or receipt of calls, as soon as the subscriber hangs up his telephone.

5

10

General

The system in connection with which the invention will be described is one in which subscribers' lines are served in common by a number of cord circuits to which they gain access by way of line finders and in which the line finder which is to be set into operation in response to a call, and consequently the cord circuit to which a calling line is to be extended, is allotted by an allotter which performs its allotting function in response to a start signal transmitted to it by the said calling line.

Moreover, in the system in connection with which the invention will be described, it will be supposed that the subscribers' lines are divided into groups of two hundred lines and that, for the service of each such group, there is assigned a suitable number of line-finders and cord-circuits, and two hundred lines of a group appearing, in multiple, in the banks of all the line-finders assigned thereto. It may be assumed that there are eight hundred subscribers' lines; consequently, there will be four groups of subscribers' lines and these four groups will be served by four groups of line-finders.

25

30

35

Still further, it will be supposed that there is, associated with each group of two hundred subscribers' lines and its associated group of line-finders, one allotter which deals, primarily with calls initiated by subscribers in its own group, allotting for use in connection therewith one of the associated line-finders, but which may be "borrowed" by other groups of lines in order that it may deal, secondarily, with calls initiated by a subscriber in such other groups of lines and may allot, for use in connection with such calls, line-finders associated, not with the group of subscribers' lines which it primarily serves, but associated with the group by which it is borrowed. Such borrowing of an allotter which primarily serves one group of two hundred lines by a line of another group occurs when the allotter which should, as its primary duty, serve the said other group of lines is either already occupied in allot-

40

45

50

55

ting a line-finder or has been put out of service on account of some derangement.

Since an allotter has to be able to allot any line-finder, according to the circumstances of a call, in any one of four groups of such, it is apparent that the service wires between the allotters and the line-finders must be multiplied over the banks of all the allotters. From this it is apparent that when a calling line demands the services of an allotter, whether of that which primarily serves it or of one which serves it as its secondary, tertiary, or quaternary duty, such calling line must, in order that the allotter shall allot a line-finder which is capable of serving the calling line, be able to inform the allotter of the identity of the group to which it belongs.

As has been stated, the line-finders serve groups of two hundred lines, that is, there appear in their banks the contacts of two hundred lines. The line-finders are of that type in which the wipers occupy one position for either of two lines and selection of one or other of the two lines is effected by a selection of one or other of two sets of wipers, one of which is in association with the contacts of one of the two lines and the other of which is in association with the contacts of the other of the two lines. From this it is apparent that when a calling line demands the services of an allotter, it is necessary that the calling line inform the allotter to which of the two sub-groups of one hundred lines, which constitute a group of two hundred lines, such calling line belongs in order that the allotter may select the correct set of wipers of such line-finder as it may allot.

Take for consideration any group of line-finders; the line-finders of this group are, in the system under description, divided into two sub-groups which may be designated respectively directly connected line-finders and indirectly connected line-finders. The directly connected line-finders terminate directly in cord-circuits; the indirectly connected line-finders terminate in the banks of secondary line-finders over which, indirectly, they reach cord circuits.

An allotter, in allotting a line-finder of the group in question always allot a directly connected line-finder if there is one available and allot an indirectly connected one only if there is no directly connected one available. The service wires of the directly connected line-finders are therefore connected to the bank of the allotter in advance of those of the indirectly connected line-finders. The allotters are, however, switches which do not necessarily return, after use, to an initial position but which under certain conditions preselect, after use in connection with one call, an idle line-finder, for use in a subsequent call or, under other conditions return to an initial position. Thus, if an allotter has been used in the operation of allotting a directly connected line-finder in one group of such, it, upon release, preselects another idle line-finder in the same group, if such exists, ready for use in a subsequent call. If such idle line finder does not exist the allotter passes through the positions occupied by indirectly connected line-finders of the same group and also, if such should lie in its path, through the positions occupied by both directly and indirectly connected line-finders of other groups to its initial position. If the allotter has been used in the operation of allotting an indirectly connected line-finder it, upon release, invariably passes through all intervening 75 positions to its initial position. Further, it may

very well happen that when an allotter is taken into use there may be available no directly connected line-finders between the position in which its wipers are standing at the time the demand occurs and that in which the first indirectly connected line-finder appears. It is therefore arranged that, before an allotter, which has started from some intermediate position, can allot an indirectly connected line-finder, it must pass through its initial position in order that it may have an opportunity of allotting a directly connected line-finder if such should be available. It may be noted that, for night service, the allotter always allot indirectly connected line-finders: this is within the general statement made above for at night the directly connected line-finders are rendered unavailable by reason of the positions, upon which are situated the cord circuits in which they terminate, being unstaffed.

Still in the system in connection with which the invention is being described, the indirectly connected line-finders are terminated, as has been stated, in the banks of secondary line-finders. Although the indirectly connected line-finders are the residue as it were, of four groups of line-finders serving four groups of two hundred lines, the secondary line-finders are divided into two groups and each group serves half of the indirectly connected line-finders. The indirectly connected line-finders may therefore be regarded as re-grouped into two groups and, in what follows, will be so regarded, the four fold grouping being now conveniently ignored.

A group of indirectly connected line-finders is served by a group of secondary line-finders in the banks of which the indirectly connected line-finders are connected in multiple.

It will be supposed that there is associated with each group of secondary line-finders one secondary allotter which deals primarily with calls extended over an indirectly connected line-finder to that group of secondary line-finders with which the allotter under consideration is associated, allotting for use in connection with such extended connection a secondary line-finder which it primarily serves. It is arranged however that the secondary allotter associated with the group of secondary line-finders under consideration may be borrowed by the other group of secondary line-finders, which it may then serve as its secondary duty, allotting for use in a connection extended to said other group of secondary line-finders a secondary line-finder of such secondarily served group of secondary line-finders.

In addition to the two secondary allotters each of which is, as already stated, associated, for primary duty, with one of the group of secondary line-finders and each of which is borrowable, for secondary duty, by the other group of secondary line-finders, there is provided a third (or as it may preferably be called additional) secondary line-finder the duty of which is to serve either of the groups of secondary line-finders when two calls are made at the same time in one group of indirectly connected line-finders. By this means the amount of a borrowing, by either group of indirectly connected line-finders, of the allotter which primarily serves the other group of indirectly connected line-finders is reduced.

As with the primary allotters (that is those which serve the directly and indirectly connected line-finders) so with the secondary allotters it is necessary that, when a secondary allotter is called upon to allot a secondary line-finder, the second-

ary allotter be informed from which group of indirectly connected line-finders the call comes in order that it may be able to allot a secondary line-finder of that group which it primarily 5 serves or of that group which it secondarily serves. It is necessary to give similar information to the additional allotter.

Unlike the directly connected line-finders which, it will be recalled, terminate directly in 10 cord circuits, the secondary line-finders terminate in the wipers of cord-seekers to the banks of which are connected cord-circuits and calling circuits, the latter of which terminate upon a night operator's position. The cord seekers are caused 15 to select, according to circumstances, a cord circuit or a calling circuit on the night operator's position by means of a wiper switching operation.

Apparatus

20 As the apparatus which it may be supposed is being used for the purpose of the system in connection with which the invention is being described is known in the art, it will not be necessary that such be described in any detail. A few remarks which will serve to identify the particular type of apparatus and which will serve to recall certain features of it should suffice.

The switches which serve as line-finders and as allotters are of a known, motor-driven quick- 30 acting type, the banks of which accommodate fifty-two contacts. To set one of these motor-driven switches into operation, a latch magnet withdraws a latch from a toothed wheel and closes a circuit for the motor magnet. To stop such a 35 switch the latch magnet opens the motor circuit and re-applies the latch. The motor and latch will not be shown in the drawings.

In the primary line-finders, the wipers are connected together in pairs, the two of a pair are 40 angularly displaced to the extent of 180°, and one wiper of a pair operates over one level whilst the other wiper of the same pair operates over another level of a bank. As one wiper of a pair leaves its 45 level the other enters its level. Thus by one complete revolution of the switch a pair of wipers serves the contacts of one hundred lines. There are as many such pairs as may be necessary.

Since the directly and indirectly connected line-finders serve two hundred lines, the wipers and banks are duplicated and one pair or the other 50 pair of two pairs of wipers is selectable by means of a switching relay. Thus either the pair of wipers which serves, say the positive, level of one hundred lines or the pair of wipers which serves the like banks of the other hundred lines may be 55 connected by the switching relay to the positive conductor of the cord, and similarly for the negative and other levels.

In the diagrams one of the wipers of a pair in 60 the line finders and the arc (representative of a level of fifty-two contacts) which it serves are shown in full and the other in dotted lines.

In the allotters and cord-seekers, the wipers are connected together in pairs, the two wipers of a 65 pair are angularly displaced to the extent of 180°, and the wipers of a pair operate successively over the same level. Thus one complete revolution of such a switch serves fifty-two contacts twice.

As the number of circuits which a primary allotter can serve is more than can be served over 70 one set of levels the levels (and their pairs of wipers) are duplicated and wiper-switching is provided. This must not be confused with the wiper-switching at the primary line-finders.

75 As the cord-seekers have to serve cord-circuits

or night calling-circuits, the wipers and banks of these switches are also duplicated, circuits of the one sort being served over one set of wipers and levels, and circuits of the other sort being served over the other set of wipers and levels and wiper- 5 switching being provided.

Circuits, general

It is now possible to refer to the accompanying circuit diagrams, and certain features thereof will 10 be referred to before a detailed description of the operation is given.

A pair of start wires $1wx$ and $1yz$ one appropriate to one sub-group of one hundred lines and the other to the other sub-group of one hundred 15 lines of a group of two hundred lines, extends to a "primary start relay group" Fig. 2. Other pairs of start wires $2wx$ and $2yz$, $3wx$ and $3yz$ and $4wx$ and $4yz$ extend from the two sub-groups of the remaining groups of two hundred lines. 20

In the "primary start relay group" are four pairs of relays SA and SB, SC and SD, SE and SF, SG and SH. Each pair of relays is associated with and controlled by one of the primary allotters in such manner that if the primary allotter is available 25 the associated pair of relays is operated. For the sake of simplicity only one of the allotters, one of the pairs of relays SA and SB, and the circuits which this pair of relays control and by which they are controlled, are fully shown: the 30 others are similarly arranged.

A primary allotter, Figs. 3 to 6, includes a group of relays A to H, Fig. 3, which control a marker, Fig. 4, in such manner as to inform the allotter in which group of two hundred lines a calling 35 line is situated. These relays also control a relay AB, Fig. 6, in such manner as to inform the allotter in which sub-group of one hundred lines a calling line is situated. The marker also serves to inform the allotter if it is serving in a primary, 40 secondary, tertiary, or quaternary capacity and whether it is to allot a directly or indirectly connected line-finder. These points will be understood later. 45

Circuit description

A description will now be given of the operations which take place when a subscriber's line becomes a calling line and which are involved in connecting the calling line to a cord circuit by 50 way of an indirectly connected line-finder, of a secondary line-finder and a cord-seeker. The calling line will be assumed to belong to that sub-group of one hundred lines which involves 55 wiper switching at the indirectly connected line-finder and to that group of two hundred lines which the primary allotter serves in its quaternary capacity. Allotter number 2 (associated with relays SC and SD) should serve the caller as its primary duty but it is supposed to be unavailable, 60 as are allotter 3 (relays SE and SF) which should as its secondary duty, and allotter number 4 (relays SG and SH) which should as its tertiary duty, serve the calling line. This will involve the supposition that the pairs of relays SC and SD, 65 SE and SF, SG and SH are released and that the pair of relays SA and SB are operated (the allotter shown in Figs. 3 to 6 being available). The starting wires appropriate to the group of lines to which that chosen for the purpose of description 70 belongs are $2wx$ and $2yz$ and that appropriate to the sub-group is $2yz$.

The example chosen for description will bring into operation the maximum of apparatus. Diversions will be made to show what would have 75

happened under other circumstances. The digressions may be passed by if desired: they will be recognized by a suitable introduction and each will be confined within a single paragraph, enclosed within brackets.

When the subscriber, whose exchange equipment is shown in Fig. 1, initiates a call, a loop is closed for his line relay LS. Relay LS operates.

Relay LS at contacts.—ls₁ connects negative by way of resistance RS to wire ps, ls₂ disconnects one source of earth from wire +s, ls₃ performs an operation which has no present interest, ls₄ disconnects negative from wire pm in the calling subscriber's multiple to render the line unavailable as a called line, and ls₅ connects earth to wire 2yz. This earth extends by way of contacts d₂ (Fig. 2), similar contacts (indicated by x) of the other alloters, sc₄, se₄, sg₄ and sa₄, to relay D, (Fig. 3). Relay D operates.

20 *Relay D at its contacts.*—d₁ closes a holding circuit for itself whereby it is rendered independent of any change in the availability of other alloters, d₂ opens its own original operating circuit so that no other line in the same sub-group can, for the moment, obtain the services of an allotter, d₃ closes an alternative holding circuit so that relay D may not be released until the allotter is available for service, d₄ disconnects negative from the so-called normal contact in bank P₁ of the line-finder shown and of all those of the same group so that such a one as may be eventually set into operation may pass through normal if necessary, d₅ (Fig. 6) closes a circuit for winding AA(I) of relay AA, and d₆ (Fig. 4) prepares a point in marking wire 10. Relay AA operates.

25 *Relay AA at its contacts.*—aa₁ performs an operation which has no present interest, aa₂ closes a circuit for relays AC and AD, aa₃ prepares a circuit for winding JA(I) of relay JA.

30 *Relay AB at its contacts.*—ab₁ performs an operation which has no present interest, ab₂ closes a circuit for winding AB(I) of relay AB, ab₃ prepares a holding circuit for winding AB(II) of relay AB, and at contacts ab₅ and ab₆ modified the marker. Relays A and C also would have suitably modified the marker. Contact aa₁ would have substantiated contact ab₄. If relay B had been operated—allotter performing quaternary duty for the sub-group other than that to which the caller shown belongs—contacts of relay B would have had the same effect as those of relay D except that the marker would have been differently operated. If relays E or G had been operated—allotter performing tertiary duty—

35 contacts e₅ or g₆ would have closed a circuit for winding AB(II) of relay AB. Relay AB would have operated and would have, at contact ab₃ closed a circuit for winding JA(II) of relay JA. Relay AA would not have been operated; therefore relays AC and AD would not have been operated and the allotter would work over its even numbered levels. If relays F or H had been operated—allotter performing secondary duty—relay JA would have been operated without relays AA, AB, AC or AD being operated. The allotter would then have worked over its even numbered levels.

40 *Relays AC and AD at their contacts.*—ac₁ to ac₅ and ad₁ to ad₃ switch out the even numbered wipers and switch in the odd numbered wipers of

the allotter since it is over these wipers that the allotter is able to serve those line-finders which serve the group of calling lines to which the calling line shown belongs, ac₆ and ad₅ close the already prepared circuit for winding JA(I) of relay JA, and ad₄ (Fig. 4) divert the marking circuit from those wires which may be served by wiper 16 to those which may be served by wiper 15.

Relay JA at its contacts.—ja₁ (Fig. 5) closes a circuit for winding KA(I) of relay KA, ja₂ (Fig. 10 3) prepares a circuit for relay TA, ja₃ opens the circuit for relays SA and SB to guard the allotter from intrusion by other calling lines, ja₄ opens a point in the circuit of winding KA(II) of relay KA to allow the allotter to pass through normal if necessary in the course of the search for an idle line-finder, and ja₅ completes the marking circuit for wire 10, which wire will be supposed to be connected in multiple to the first group of contacts in the first half of bank 15 and to be appropriate to those directly connected line-finders that are able to serve the group of subscribers' lines to which the caller belongs. Relay KA operates.

Relay KA at its contacts.—ka₁ closes a holding circuit for itself, to a timing contact z, ka₂ closes a circuit for latch magnet MUA (from earth via contacts la₁, ma₁, ka₂, ga₄, ae₁, magnet MUA, to negative), ka₃ substantiates contact ja₃, ka₄ closes a circuit for relay TA which relay however, is short circuited in all positions of the allotter except its normal position, which position, for the present it will be supposed not to be occupying, ka₅ prepares a circuit, at present short circuited by contact la₁ and ma₁ for relays MA and NA, and ka₆ closes a point in the circuit of winding KA(II) of relay KA for a purpose which will be referred to later. Latch magnet MUA energizes.

(Latch magnet MUA, when energized, serves to withdraw a latch from the motor (not shown) of the allotter and to complete the circuit of that motor and, when deenergized, to open the circuit of and to relatch the motor.)

Under our present supposition, that there are no idle directly connected line-finders in the group, marked over wire 10, which can serve the caller, the allotter will be required to allot an indirectly connected one. It will therefore rotate its wipers, which may be supposed to be standing at a position about half way through those which are associated with and marked by wire 19, past all the intervening directly connected line-finders, past the indirectly connected line-finders of the same group, past the next group of directly and indirectly connected line-finders (namely those which in bank 15 are adapted to be marked over wires 9 and 18), to normal. The wipers will rotate past these contacts because wires 19, 9 and 18 are not marked. It will be seen that, although an indirectly connected line-finder is wanted, the allotter has ignored them and has gone to normal. This is in order that the allotter may ascertain that those directly connected line-finders which lay behind the position in which the allotter stood when called on for service were actually not idle. The allotter obviously ignored the directly and indirectly connected line-finders which it serves in the second half of its level 15 because such line-finders are incapable of serving the group of lines to which the caller belongs.

As the allotter passes through its normal position it opens its off-normal contacts ON (Fig. 3) thereby removing the short circuit from relay TA. Relay TA which is a high speed relay, operates.

Relay TA at its contact.—ta₁ substantiates the

removal of short circuit from its own winding, in order that it may remain operated after contact ON closes, and closes a circuit for relay UA. Relay UA operates.

- 5 *Relay UA at its contacts.*—ua2 connects up marking wire 19 (wires 10 and 19 being now marked), and ua1, ua3 and ua4 perform similar operations for the other groups but these are of no interest for the present purpose.
- 10 The allotter eventually reaches a position in which wiper 15 is in connection with one of the contacts to which wire 19 is connected and wiper 13 is in connection with a contact, in a corresponding part of level 13, to which a wire la of an idle indirectly connected line-finder is connected, the idle condition being indicated by negative on the said wire la. In this position the following circuit is closed: earth, through rectifier RE, by way of contacts ma5, ja5, ad4, ab5, d6, ua2, wire 19, a contact in level 15, wiper 15, contact ad3, windings LA(I) and LA(II) of relay LA, contact ac5, wiper 13, a contact in level 13 of the allotter, wire la of the idle indirectly connected line-finder, (Fig. 7), contact hf2, resistance RF, wire tf (Fig. 9), contact gc1 (Fig. 9), to negative. Relay LA (Fig. 5) operates.

It may here be conveniently shown that had the allotter encountered an idle directly connected line-finder, either as it passed through the 30 positions between that at which it stood when first taken into use and that of the first indirectly connected line finder or, thereafter, as it passed through the positions between its normal position and that of the first indirectly connected 35 line-finder, the circuit for relay LA would have been from earth, through rectifier RE, by way of contacts ma6, ja5, ad4, ab5, d6, wire 10, a contact in level 15 and wiper 15 of the allotter, contact ac5, wiper 13 and a contact in level 13 of the allotter, wire la of such idle directly connected 40 line-finder (Fig. 7) there being no difference between directly and indirectly connected line-finders so far as their construction and circuits are concerned, wire pf (Fig. 15), key HK, contact ma5, wire pb, contacts pf1 and ra1, and resistance RO to negative. Relay LA would have operated. It will be self-evident that if wiper 15 had been in a position beyond those to which wires 10 and 19 are connected, that is in a position corresponding to wires 9 and 18, the wipers would have to 45 pass through normal to reach a position in which it could serve a directly or indirectly connected line-finder suitable for the purpose in hand. Relay UA would thus become operated but, of course, a directly connected line-finder would have been allotted before an indirectly connected one were reached.

Relay LA (Fig. 5) at its contact.—la1 short circuits its own winding LA(I), applies earth through its own winding LA(II), which is of low 50 resistance, to wire la in order to render the line-finder unavailable to other allotters and to hold relay LA operated, removes the short circuit from the windings of relays MA and NA, and opens the circuit of latch magnet MUA. Although there is 55 still a circuit by way of relays MA and NA for magnet MUA, the magnet will release. Relays MA and NA operate.

Magnet MUA releasing arrests the motion of the allotter.

70 *Relays MA and NA, which act as one relay, at their contacts.*—ma1 opens a further point in the circuit of the latch magnet against the release of contact la1, ma2 (Fig. 6), performs an operation of no present interest, since in the supposed case, 75 relay AB is not operated, ma3 short circuits wind-

ing LA(II) of relay LA and applies full earth to wire la to maintain the indirectly connected line-finder of Fig. 7 unavailable to other allotters, ma4 close alternative circuits for relays AC and AD, and relay JA, ma5 open the marking circuit, 10 na1 (Fig. 5) prepare a circuit for relay PA, na2 close a circuit (earth, via contacts pa1, qa1, na2, ac2, wiper 3 of the allotter and a contact in its level 3, wire muf, latch magnet MUF of the line-finder, negative), for magnet MUF, na3 prepare 15 a circuit to wire hf (Fig. 7), na4 close a circuit via wire def for winding DF(I) of relay DF, na5, prepare a circuit to wire rf, and na6 close a circuit from negative, via contacts na6, ad2, wiper 11 of the allotter and a contact in level 11, wire sf 15 (Figs. 7 and 8), relays SO and ST (Fig. 10) to earth. Latch magnet MUF energizes. Relays DF and SO operate. (Relay ST does not operate.)

Latch magnet MUF controls the motor of the 20 line-finder in the same manner as that in which magnet MUA controlled that of the allotter. Relay DF effects wiper switching, and relay SO controls the secondary allotter. The line finder and the secondary allotter operate simultaneously. 25 It is inconvenient to consider these operations concurrently; consideration of the secondary allotter will be deferred.

Relay DF at its contacts.—df1 prepares a holding circuit for its winding DF(I), df2 prepares a 30 holding circuit for its winding DF(II) the purpose of which will be explained later, and df3 to df6 effects the necessary change over of the wipers.

(Relay DF would not have been operated if the caller had been in any of the sub-group of one 35 hundred lines the starting wires of which are 1WX, 2WX, 3WX or 4WX for then one of the relays A, C, E or G (Fig. 3) would have been operated and, as shown in a preceding digression, would, at contacts a5, c5, e5 or g5 have brought 40 about the operation of relay AB which relay, at its contacts ab2 would have opened the circuit for relay DF.)

Latch magnet MUF unlatches, and starts, the 45 motor of the indirectly connected line-finder, which is assumed to be resting in a position other than that of the line of the caller. The line-finder wipers are rotated and, when they encounter the contacts of the caller, a circuit is completed from earth, through rectifier RE (Fig. 5), winding PA(I) and PA(II) of relay PA, contacts na1 and ac1, wiper 1 and a contact in level 1 of the allotter, wire pc (Fig. 7) contact df5, (say) the full line wiper and level PI of the line-finder, wire ps of the calling line, contacts ls1 and ks5, resistance RS to negative. Relay PA (Fig. 55) operates.

Relay PA at its contacts.—pa1 short circuits winding PA(I) of relay PA, connects earth to low resistance winding PA(II) of relay PA to protect 60 the calling line from intrusion and to hold relay PA and opens the circuit of latch magnet MUF whereby the line-finder is brought to rest.

(Wire rf of directly connected line-finders is 65 permanently connected to earth so that, had the line-finder which the allotter allotted been a directly, instead of an indirectly, connected one, relay RA (Fig. 5) would have operated when contact na5 became closed. Relay RA would have at its contacts: ra1 prepared a circuit for relay 70 QA, and ra2 substantiated contact ja3. When, under these conditions, relay PA should operate it would, in addition to the operations noted above, remove a short circuit from relay QA and this relay would operate, at this time, in series 75

with latch magnet MUF. The results of the operation of relay QA will be described when its operation is referred to in connection with the indirectly connected line-finder.

5. Nothing more happens in the primary allotter until the secondary allotter has allotted a secondary line-finder.

The indirectly connected line-finder having been set on the contacts of the calling line, consideration may now be given to the secondary allotter which was left with its relay SO operated.

(Relay ST operates only if two primary allotters serving the same group of indirectly connected line-finders, which, it will be recalled are, so far as the secondary allotters are concerned, divided into two groups, are calling simultaneously for the services of a secondary allotter.)

Relay SO (Fig. 10) at its contacts.—so1 (Fig. 11) closes a circuit for relay I (Fig. 12). Relay I 20 operates.

Relay I at its contacts.—i1 closes a holding circuit for itself whereby it is rendered independent of contact s1; i2 (Fig. 11) opens its own original operating circuit so that the starting circuit (contact so1) shall not be passed onto a second allotter, i3 (Fig. 13), closes a marking circuit to wire 10 to inform the secondary allotter which half of its levels it has to serve, and i4 (Fig. 12) closes a circuit for relay EB. Relay EB operates.

30. *Relay EB at its contacts.*—eb1 opens the circuit of relay SJ so that this relay releases and protects the allotter from calls for secondary duty (it is protected from further calls for primary duty by contact i2) and prepares a holding circuit for relay EB, eb2 prepares a circuit, at present open at contact s2, for latch magnet MUB, eb3 closes a circuit for relay PE, eb4 closes a circuit for relay UB, eb5 places a short circuit across winding QB(I) of relay QB to render this relay retarded 40 in release, and eb6 prepares a circuit for relays FB (Fig. 13) and GS (Fig. 8). Relay UB operates if the allotter is in a position other than normal with results of no present interest. Relays FB and GS operate if, or as soon as, wiper 8 of the 45 secondary allotter is associated with a contact of the half of level 8 to which wire 10 is multipled and if, or as soon as, wiper 7 of the secondary allotter is associated with a contact of the corresponding half of level 7 to which a wire gs of an available secondary line-finder is connected. Relay PE (Fig. 13) operates.

50. *Relay PE at its contacts.*—pe1 closes a circuit for winding QB(II) of relay QB, and pe2 (Fig. 12) substantiates contact eb1. Relay QB operates.

55. *Relay QB at its contacts.*—qb1 guards itself against the opening of contact rb3, qb2 prepares a short circuit for relay PE, qb3 prepares a circuit for relay S, and qb4 closes a circuit for retarded operating relay RB. Relay RB after a delay, operates.

60. *Relay RB at its contacts.*—rb1 closes a holding circuit for itself, rb2 prepares a short circuit across its own winding, rb3 opens the original 65 circuit for relay QB which relay is now held by contact qb1, rb4, prepares a circuit to wiper 3 of the secondary allotter, rb5 closes a circuit for relay S, and rb6 completes a short circuit across relay PE. Relay PE does not release immediately. 70 Relay S operates. The reason for this chain of operations and of the very retarded release of relay PE will be understood later.

75. *Relay S at its contacts.*—s1 opens the circuit of relay PE and closes a holding circuit for itself, s2 closes a circuit from earth at contact fb1, sup-

posing relay FB not to be operated, by which relay HB is short circuited and s3 performs an operation of no present interest.

The secondary allotter may not or may have its wipers already in association with the contacts of a suitable and available secondary line-finder. If it has not, latch magnet MUB will be energized and the allotter will rotate to find a suitable and available secondary line-finder. If it has, or as soon as it has, relays FB and GS will 10 operate as described above.

Relay GS at its contacts.—gs1 removes one source of earth from wire gc (Fig. 9) and gs2 prepares a circuit for relay NS.

(When all secondary line finders are in use, all 15 sources of earth are removed from wire gc and relay GC (Fig. 9) operates. Relay GC at its contact gc1 removes negative from wires tf of all indirectly connected line-finders served by the secondary line-finders of the group to which that shown in Fig. 8 belongs so that the primary allotter finds these unavailable. Relay NS comes into operation only when night service is in force.)

25. *Relay FB (Fig. 13) at its contact fb1* opens the circuit of latch magnet MUB, removes the short circuit from relay HB and short circuits winding FB(I) of relay FB. Latch magnet MUB releases and arrests the motion of the allotter and relay HB operates in series with magnet MUB. 30

35. *Relay HB at its contacts.*—hb1 substantiates contact fb1 insofar as that contact is related to relay HB and to latch magnet MUB, hb2 prepares a circuit from earth through rectifier RC (Fig. 13), windings JB(I) and JB(II) of relay JB, contact hc2, wiper 1 and the contact in level 1 at which wiper 1 is resting, to wire am, hb3 closes a circuit from earth, by way of contact jb1, lb2, lb1, nb2, hb3, wiper 5 and the contact in level 5 at which the allotter is at rest, wire mus, latch magnet MUS which is the latch magnet of the secondary line finder, to negative, hb4 prepares a circuit from earth, through rectifier RD, by way of windings KB(I) and KB(II) of relay KB, contact hb4, wiper 4 and the contact in level 4 at which the allotter is at rest, wire kb, contacts hs1 and ns4 to wire ps, hb5 closes a circuit from earth by way of contacts kbl, mb1, hb5, wiper 6 and the contact in level 6 at which the allotter is at rest, wire muc, latch magnet MUC, which is the latch magnet for the cord seeker, to negative, hb6 opens the circuit of relay UB, and hb7 provides a locking circuit for relay EB.

40. Latch magnet MUS may or may not operate as the secondary line-finder is not or is already serving the indirectly connected line-finder which called for service. If it is already, or as soon as it is, serving that indirectly connected line-finder, the circuit above noted as prepared for relay JB to wire am is further extended by way of wiper AM of the secondary line-finder, the appropriate contact in level AM, wire rf (Fig. 7), the appropriate contact in level 9 (Fig. 5) of the primary allotter, wiper 9, contacts ad1 and na5, and relay RA shunted by resistance RR, to negative. Relays JB (Fig. 13) and RA (Fig. 5) operate. (The effects of the operation of relay RA will be described later. All that need be stated at present is that it eventually brings about the breaking at contact na5, of the circuit in which it and relay JB operated.)

45. Relay JB at its contact jb1 short circuits winding JB(I) of relay JB, provides a holding circuit by way of winding JB(II) for relay JB, and by raising the potential of the contact in level 50

AM of the secondary line-finder protects the indirectly connected line-finder from intrusion by other secondary line-finders, and opens the circuit of latch magnet MUS and removes a short circuit from relay LB. The secondary line-finder is thus brought to rest and relay LB becomes operated in series with the latch magnet MUS.

Relay LB at its contact.—*lb1* closes a holding circuit for itself via resistance RL, *lb2* substantiates contact *jb1* insofar as that contact is related to relay LB and to latch magnet MUS, *lb3* closes a circuit for relay NB, *lb4* connects earth by way of wiper 2 and level 2 of the secondary allotter to wire *pl* and thence by way of wiper P and level P of the secondary line-finder to wire *pf* to hold relay HF and winding DF(I) of relay DF in the indirectly connected line-finder, *lb5* and *lb6* bridges contacts *nb3* and *nb4* to guard relays I and EB against release when relay NB becomes operated and *lb7* performs an operation of no present interest.

Relay NB at its contacts.—*nb1* further prepares the circuit already partly prepared by contact *rb4* to wiper 3 of the secondary allotter, *nb2* opens a point in the original operating circuit of relay LB to guard this relay against an eventual release of contact *lb1*, *nb3* and *nb4* performs operations of no present interest, and *nb5* substantiates contact *eb1* insofar as that contact is related to relay SJ. (All this occurs whilst relays PE and relays which it controls are still operated.)

At the same time that these operations, which include a possible search by the secondary line-finder for the calling indirectly connected line-finder and which include either the immediate or eventual operation of relays JB (Fig. 13) and R (Fig. 5) followed by the operation of relay LB, have been taking place, latch magnet MUC may or may not have operated as the cord seeker may not or may be already serving an idle cord-circuit. If it is already, or as soon as it is, serving an idle cord-circuit, the circuit above noted as prepared for relay KB to wire *ps* becomes further extended by way of wiper PC of the cord-seeker (Fig. 8), wire *pc* (Fig. 15), contact 1 of key HK, contacts *mc5*, *pf1*, and *ra1* and resistance RO, to negative. Relay KB (Fig. 13) operates.

Relay KB at its contact kb1 short circuits winding KB(I) of relay KB, provides a holding circuit by way of winding KB(II) for relay KB, and by raising the potential of the contact in level PC of the cord-seeker protects the selected cord from intrusion by other cord-seekers, and opens the circuit of latch magnet MUC and removes a short circuit from relay MB. The cord-seeker is thus brought to rest and MB becomes operated in series with the latch magnet.

Relay MB at its contacts.—*mb1* substantiates contact *kb1* insofar as that contact is related to relay MB and to latch magnet MUC, and *mb2* places a bridge across contact *lb2* for the eventual release of relay LB.

By this time relay RA in the primary allotter should have brought about the opening of contact *na5* and the consequential release of itself and of relay JB in the secondary allotter.

Relay JB at its contact *jb1* provides a short circuit for relay LB. Relay LB becomes released.

Relay LB at its contacts.—*lb1* and *lb2* performs restorative functions, *lb3* opens the circuit of relay NB which, however, is of retarded release, and closes a circuit by way of wiper and level 3 of the secondary allotter for relay HS (Fig. 8), *lb4* removes earth from wire *pl*, *lb5* and *lb6* (Fig. 12)

opens the circuits of relays I and EB, and *lb7* short circuits relay RB. Relay HS (Fig. 8) becomes operated and relays I and EB become released. Relay RB becomes released after a delay.

Relay HS at its contacts.—*hs1* closes a holding circuit for itself to wire *ps* and opens the circuit of relay KB, *hs2* substantiates contact *gs1* insofar as that contact is related to relay GC, (Fig. 9) and replaces the earth removed from wire *pl* by contact *lb4*; *hs3*, *hs4* and *hs5* extends wires *+f*, *-f*, and *mf*, to wires *+s*, *-s*, and *ms*; *hs7* performs an operation of no present interest; and *hs8* prepares a circuit for relay CH. Relay KB releases. The calling subscriber's line is now extended through an indirectly connected and a 15 secondary line-finder (Figs. 7 and 8) to a cord circuit (Fig. 15).

Returning now to the secondary allotter, relay I at its contacts performs restorative operations, relay EB at its contacts performs restorative operations including the preparation of the circuit for relay SJ, (Fig. 11) the opening of the circuit for relays FB, (Fig. 13) and GS (Fig. 8) and of the circuit for relays HB and S. Relay KB short circuits relay MB. Relay HB performs restorative operations. Relay NB, which, by now, will have become released, performs restorative operations, including the further preparation of the circuit for relay SJ.

Relay PE which will have become released by 30 now, performs restorative operations including the closure of the circuit for relay SJ, and the opening of the circuit for relay QB. Relay QB performed restorative operations. Relay RB also performed restorative operations. The secondary allotter is thus restored to its normal condition.

(It may here be mentioned that if for some reason or other the secondary line-finder had been unable to find the calling indirectly connected line-finder, relay JB would not have operated and therefore relay LB would have remained unoperated. Relay PE would, as was described above, have become short circuited by contacts *qb2* and *rb6* when those relays became 40 operated and would consequently, after a delay, have become released. Relay PE would at its contact *pe1* have opened the circuit of relay QB which, after a delay due to its winding QB(I) being short circuited, would have become released. Relay QB at its contact *qb3* would have 50 closed a circuit for relay TB and at *qb4* short circuited relay RB. Relay RB, after a delay, would have become released and would have at its contacts *rb4* opened a possible circuit for relay HS 55 and *rb5* closed a circuit for relay NB. Relay NB would have become operated and would have at its contacts *nb3* and *nb4* opened the circuits of relays I and EB (for which no guards would have been closed by relay LB), and *nb5* kept open 60 the circuit of relay SJ. Relays I and EB would have released. Relay I would have at its contact *i2* (Fig. 11) reclosed the start circuit which would be consequently passed on by the contacts *sj1* and *sk1* to allotter number 2. Relay EB 65 would have brought about the release of the allotter which failed.)

The description of the primary allotter was left at the point that its relay PA had operated and had, inter alia opened the circuit of latch magnet MUF. It was also mentioned in the description of the secondary allotter, that relay RA in the primary allotter became operated. The effects produced by this operation will now be considered.

Relay RA at its contacts.—*ra1* closes a circuit for relay QA in series with latch magnet MUF, and *ra2* substantiates contact *ja3*. Relay QA becomes operated but not latch magnet MUF.

- 5   *Relay QA at its contacts.*—*qa1* closes a holding circuit via resistance RQ for relay QA, *qa2* opens the circuit of winding KA(I) of relay KA and closes a circuit for relay HF (Fig. 7), *qa3* substantiates contact *ja3*, *qa4* opens the circuit of relays MA and NA, *qa5* closes a circuit for winding AE(I) of relay AE. Relay KA becomes released, relay HF becomes operated, relay MA and NA become released, and relay AE becomes operated.

- 10   *Relay KA at its contacts.*—*ka1* to *ka3* and *ka5* to *ka6* performs restorative operations and *ka4* opens the circuit of relays TA and UA. Relays TA and UA become released.

- 15   *Relay HF at its contacts.*—*hf1* closes a holding circuit for itself to wire *pf* to which wire earth has by now been connected either by relay LB in the secondary allotter or by relay HS in the secondary line-finder, *hf2* closes a holding circuit for winding DF(I) of relay DF, *hf3*, *hf4* and *hf6* connects the wipers of the primary line-finder through to the secondary line-finder and *hf5* connects earth to wires *ps* and *pc*. The earth connected to wire *pc* short circuits winding PA(II) of relay PA. Relay PA becomes released.

- 20   *Relays MA and NA at their contacts.*—*ma1* prepares a circuit for latch magnet MUA as will appear, *ma2* to *ma4* perform restorative operations, *ma5* reprepares the marking circuit as will appear, *na1* performs a restorative operation, *na2* open a point in the circuit of latch magnet MUF to guard that magnet against an eventual release of relay QA, *na3* and *na4* perform restorative operations, *na5* open the circuit of relay RA, and *na6* perform a restorative operation. Relay RA becomes released.

- 25   *Relay AE at its contacts.*—*ae1* removes a short circuit from winding AE(II) of relay AE, *ae2* opens the circuit of winding JA(I) of relay JA, *ae3* substantiates contact *ja3*, *ae4* places a bridge across contact *ja5* to maintain a marking potential on wire 10, *ae5* prepares a circuit for latch magnet MUA, *ae6* performs an operation of no interest in the case under consideration, *ae7* closes a holding circuit for relay D (Fig. 3) which circuit is independent of the condition of start wire 2yz, and *ae8* prepares a circuit to the initial contacts of level 13.

30   Relay TA performs a restorative operation.

- 35   Relay UA performs restorative operations including particularly, the disconnection of marking wire 19 from marking wire 10.

40   Relay PA at its contact *pa1* short circuits relay QA. Relay QA becomes released.

45   Relay RA performs restorative operations.

- 50   *Relay QA at its contacts.*—*qa1* to *qa3* performs restorative operations, *qa4* closes a circuit from earth at contact *la1*, by way of contact *ma1*, *ae5*, *qa4*, winding AE(II) of relay AE and of latch magnet MUA, to negative, and *qa5* opens the circuit of winding AE(I) of relay AE which relay is however held over its winding AE(II). Latch magnet MUA becomes energized.

- 55   *Relay JA at its contacts.*—*ja1* to *ja3* and *ja5* performs restorative operations, and *ja4* completes the connection of negative to the initial contact in level 13.

- 60   Latch magnet MUA unlatches, and completes the motor circuit of the allotter whereby the allotter is driven to its initial position. When 65 the initial position is reached, a circuit is com-

pleted from earth at initial contact in level 15, by way of wiper 15, contact *ad3*, windings LA(I) and LA(II) of relay LA, contact *ac5*, wiper 13, initial contact in level 13, contacts *ja4* and *ka6*, resistance RK, to negative. Relay LA becomes 5 operated.

65   Relay LA at its contact *la1* opens the circuit of latch magnet MUA and of winding AE(II) of relay AE and short-circuits winding LA(I) of relay LA. Latch magnet MUA and relay AE 10 becomes released.

70   Latch magnet MUA opens the circuit of the motor of, and relatches, the allotter.

75   *Relay AE at its contacts.*—*ae1* and *ae2* performs restorative operations, *ae3* closes the already prepared circuit for relay SJ (Fig. 11), *ae4* to *ae6*, performs restorative operations, *ae7* opens the holding circuit of relay D, and *ae8* removes negative from the initial contact in level 13 and opens the circuit of winding LA(II) of 20 relay LA. Relay SJ operates and relays D and LA released.

80   Relay SJ reconnects the start wires *wx* and *yz* to relays A to H.

85   *Relay D at its contacts.*—*d1* to *d4* performs 25 restorative operations, *d5* opens the circuit of winding AA(I) of relay AA, and *d6* performs a restorative operation.

90   Relay LA performs restorative operations.

95   *Relay AA at its contacts.*—*aa1* performs a restorative operation, *aa2* opens the circuits of relays AC and AD, and *AA3* performs a restorative operation. Relays AC and AD become released.

100   Relays AC and AD perform restorative operations (mainly wiper switching).

105   (If the allotter had allotted any directly connected line-finder of a group, except the last directly connected line-finder of that group instead of, as has been supposed, an indirectly connected line-finder, it would, in travelling towards its initial position, have passed the contacts of intervening directly connected line-finders of the group from which it had just previously allotted one. If 110 one of these intervening directly connected line-finders had been idle, that is had had negative potential on its wire *la*, the following circuit would have been completed, namely earth by way of rectifier RE, contacts *ma5*, *ae4*, *ab5*, *d6*, wire 10, a contact in level 15 to which wire 10 is multipled, wiper 15, contact *ad3*, windings LA(I) and LA(II) of relay LA, contact *ac5*, wiper 13 in the position in which it encountered the contact of the idle directly connected line-finder, to negative on wire *la* of that line-finder. Relay LA 115 would have operated with results as above. The result would have been that the allotter, instead of going to its initial position, would have pre-allotted an idle directly connected line finder ready for use in anticipation that the next call 120 would originate from the same group.)

125   (It is here convenient to explain that, if the allotter has been unable to find a suitable line-finder, either directly connected or indirectly connected, in an idle condition, it would continue 130 to rotate until either the contacts designated *z*, which are timed contacts, opened or the calling subscriber hung up. In the former case, one of the contacts *z* would have opened the circuit of relay KA whereby the circuit of the latch 135 magnet would have been opened and other restorative operations would have been performed. In the latter case, relay D would have become released with results leading up by way of the release of relay AA to the release of relay JA. 140

5 Relay JA at its contact *ja4* would have prepared a circuit for relay LA in the initial position of the allotter as follows: earth from initial contact in level 15, wiper 15, contact *ad3*, windings LA(I) and LA(II) of relay LA, contact *ac5*, wiper 13 and initial contact in level 13, contacts *ja4* and *ka6*, winding KA(II) to negative. The current in winding KA(II) of relay KA would be in opposition to that in winding KA(I) and thereby 10 relay KA would have become released.)

10 The primary allotter is thus released as is also the secondary allotter. It will be recalled that a primary allotter requires from a line-finder, in order that it may recognize the line-finder as being available for service, negative on wire *la*. A secondary allotter requires from a secondary line-finder negative on wire *gs*.

15 Subscriber's lines are of two sorts, that is they have different facilities, and they will be termed 20 A and C subscribers respectively. The meters MS of A subscribers are connected to negative and requires earth impulses from the cord circuit for their operation: those of C subscribers are connected to earth and requires negative impulses for their operation. It will be assumed 25 that the caller is an A subscriber.

30 As soon as a calling subscriber's line has been extended to a cord-circuit (Fig. 15) either by a directly connected line finder by the closure 35 of contacts *hf3*, *hf4* and *hf6* or by an indirectly connected and secondary line-finder and cord-seeker by the closure of contacts *hs3*, *hs4* and *hs6* and *hs8*, *hs4* and *hs5*, circuits will be completed for winding LC(I) and LC(II) of relay LC 40 and for winding BT(I) of relay BT, the latter circuit being in series with meter MS. Relays LC and BT become operated. Moreover, the caller receives calling tone. The subscriber's meter does not become operated in series with relay BT.

45 *Relay BT at its contacts.*—*bt1* prepares a circuit for winding BT(II) of relay BT, *bt2* prepares a circuit for calling lamp AC and opens a possible circuit for calling lamp CC, and *bt3* prepares a point in the meter circuit to wire *mc* to meter a call to an A subscriber (earth connection).

50 (If the calling line were a C line, no circuit would have existed for relay BT, lamp AC would not have become switched in and lamp CC would 55 not have become switched out. The metering circuit would have been left for the metering of a call to a C subscriber (negative connection).)

55 *Relay LC at its contacts.*—*lc1* closes a circuit for relay BC, *lc2* opens a point in the circuit of lamp CC which is also the supervisory lamp for the calling side of the connection and *lc3* and *lc4* opens circuits which have no present 60 interest. Relay BC becomes operated.

65 *Relay BC at its contacts.*—*bc1* connects earth to wire *pc* (or *pf*) to render the cord circuit unavailable to other calling lines, *bc2* performs a preparatory operation, *bc3* opens a point in the 70 meter circuit for either an A or a C subscriber, *bc4* closes a circuit for lamp AC and for relay PC (Fig. 16), *bc5* closes a circuit for windings MC(I) and MC(III) of relay MC and for winding NC(I) of relay NC, and *bc6* removes one source of earth from relay CG, (Fig. 9). Lamp AC glows and relay PC becomes operated. Relays MC and NC do not become operated.

75 (This operation of removing earth from relay CG is protective operation. If earth is removed

entirely from relay CG, that relay will operate and render further secondary line finders, which serve the cords concerned, unavailable.)

80 Relay PC at its contacts *pc1* closes a circuit for relay PF. Relay PF becomes operated. 5

85 *Relay PF at its contacts.*—*pf1* substantiates contact *bc1*, *pf2* and *pf3* disconnects calling tone from the cord-circuit and connects the cord-circuit to the operator's service circuit CP, *pf4* disconnects earth from relay BC but this relay still 10 holds to earth at release key RK, *pf5* opens the circuit of relay PD, and *pf6* closes a circuit which will be described later and which causes three so-called "pips" of tone to be connected to the calling line via the cord, and causes the last 15 of these pips to be heard by the operator. The three pips are to notify the caller that he may give in the number he requires and the one pip is to notify the operator that a number is about 20 to be given in.

25 It should be explained that the cord circuits on an operator's position are divided into two divisions which may be termed PC-cords and PD-cords because, when a call arrives on a PC-cord, relay PC operates and, when a call arrives on a PD-cord, relay PD operates. When a call arrives on a PC-cord, contact *pf1* connects earth to all the PC-cords so that no other PC-cord can be taken into use, that is the PC-cords are marked as unavailable to the cord-seekers. PD- 30 cords are not yet rendered unavailable but relay PD cannot become operated nor can the calling lamp of a PD-cord be lit. Moreover, the earth, connected by the relay BC of a calling PD-cord to the wire *pc* of such PD-cord, is fed 35 by way of wire *pd* to other PD-cords. It thus arises that the operator can receive one visible call on a cord of one sort and one invisible call on a cord of the other sort.

40 When the operator has ascertained the caller's requirements and has taken up the plug of the cord to which the caller is connected, which cord is identified by the glowing lamp AC, she will insert this plug into the jack, such as JM, of the wanted subscriber's line. That line may 45 be free, in which case there will be negative potential connected to the private wire *pm*, or it may be already engaged, in which case there will be positive potential connected to that wire. These conditions may be verified by reference to 50 Fig. 1, the line there shown being, for the purpose, regarded as that of the wanted subscriber.

55 When the operator lifts the plug from its seat on the plug-shelf, contact *ps* becomes closed and completes a circuit for winding BT(II) of relay BT (already operated) and prepares other holding circuits.

60 Suppose the wanted line to be free, then when the plug is inserted into jack JM, a circuit will become completed from earth, via contact *bc5*, 65 winding NC(I) and MC(I) of relays NC and MC, contact *mc9*, sleeve of the plug and of jack JM, wire *pm* (Fig. 1) regarded as the equipment of the wanted line, contacts *ls4* and *ks5*, resistance *RS* to negative. Windings LS(II) 65 of relay LS and KS(II) of relay KS in series are in parallel with contacts *ks5* and resistance *RS*. Relays NC, MC, LS and KS operate.

70 *Relays LS and KS at their contacts.*—*ls2* and *ks2* disconnect earth from wire +s of the wanted line, *ls3* and *ks4* disconnect winding LS(I) and KS(I) from wire -s, *ks3* guard winding LS(II) and KS(II), *ks4* open the circuit to the start wire, and *ks5* disconnect negative via resistance *RS* from wire *pm*.

Relay MC at its contacts.—*mc1* closes a circuit for winding MC(II) for holding relay MC operated, *mc2* and *mc3* disconnects the cord-circuit from the operator's service circuit, *mc4* closes a circuit for called supervisory lamp CS, *mc5* disconnects wire *pc* from the common position equipment so that any earth connected to wire *pc* is not fed to wires *pc* of other PC-cords, *mc6* disconnects winding BT(I) from wire *mc*, *mc7* closes a circuit for retarded release relay JC, *mc8* closes a holding circuit for relay BC, *mc9* opens the circuit for windings NC(I) and MC(I) of relays NC and MC, and *mc10* substantiates contact *bc6*. Lamp CS glows and relay JC becomes operated.

Relay NC at its contacts.—*nc1* closes a circuit for winding NC(II) of relay NC to hold this relay, *nc2* and *nc3* connects the plug to contacts *fc2* and *fc3*, *nc4* closes a sneak circuit for ringing tone, *nc5* connects earth to the plug and thus to wire *pm* to mark the wanted line busy.

Relay JC at its contacts.—*jc1* connects earth to wire *pc* in addition to that already connected by contact *bc1*, *jc2* and *jc3* connects a source 25 of ringing current, over leads *rc* and winding FC(I) of relay FC, to the wanted line, *jc4* closes a further point in the meter circuit, *jc5* performs an operation of no present interest, and *jc6* disconnects the calling lamp AC and relay PC. The 30 calling lamp darkens and relay PC becomes released, and the wanted subscriber's bell is rung.

Relay PC at its contact *pc1* opens the circuit of relay PF. Relay PF becomes released.

Relay PF at its contacts perform restoratory 35 operations which include the preparation of the circuit of relay PD so that an invisible call on a PD-cord, if there be one, may become visible.

Further operations depend upon the behaviour of the calling or called subscribers. Normally 40 the called subscriber replies.

When the called subscriber replies, a circuit is completed, through the loop of his telephone instrument, for relay FC. Relay FC operates.

Relay FC at its contacts.—*fc1* closes a circuit 45 for winding FC(II) of relay FC, *fc2* and *fc3* disconnects ringing leads *rc* and connects the plug (and thus the called subscriber) through to the feeding bridge consisting of relay DC and coil RC and also to the calling line, *fc4* closes a 50 point in the meter circuit alternative to that closed by contact *nc1*, *fc5* prepares an alternative circuit for winding NC(II) of relay NC which it renders independent of contact *bc2*, and *fc6* prepares an alternative circuit for 55 winding LC(I) of relay LC. Relay DC becomes operated.

Relay DC at its contacts.—*dc1* closes the alternative circuit for winding NC(II) of relay NC, *dc2* opens the circuit of the called supervisory lamp CS, and *dc3* and *dc4* prepares circuits which have no present interest.

When the conversation is ended, either subscriber can, by hanging up his telephone, render his own line available, for use either for the initiation or receipt of calls. For rendering the line finders available it is necessary that both subscribers hang up their telephones.

Suppose that the called subscriber hangs up his telephone first. Relay DC becomes released 70 and at its contact *dc1* opens the circuit of winding NC(II) of relay NC and *dc2* closes the circuit for supervisory lamp CS. Lamp CS glows and relay NC after a delay, becomes released.

Relay NC at its contacts performs restoratory 75 operations, only two of which need be consid-

ered namely that at contact *nc5* it removes earth from wire *pm* of jack JM and thus releases the called subscriber's relays LS and KS, and at contact *nc7* appears to effect a change in the meter circuit which, however, is guarded by contact *fc4*. By the release of relays LS and KS, the called subscriber is enabled to receive and to initiate further calls.

When the calling subscriber hangs up his telephone relay LC becomes released.

Relay LC at its contacts *lc1* opens the circuit of relay BC, and *lc2* closes the circuit of supervisory lamp CC. Lamp CC glows and relay BC, after a delay, becomes released.

Relay BC at its contacts.—*bc1* removes one 15 source of earth from wire *pc*, *bc2* opens the circuit of relay JC, *bc3* closes the meter circuit for an A subscriber by connecting earth via contacts *bt3*, *jc4*, *bc3*, *fc4*, to wire *mc*, *bc5* opens the circuit of windings MC(I) and MC(III) of relay MC and of winding NC(I) of relay NC, and *bc4* and *bc6* performs restoratory operations. The calling subscriber's meter becomes operated and relay JC, after a delay, becomes released.

Relay JC at its contacts.—*jc1* removes earth 25 from wire *pc* (or *pf*) and so from relay HS (Fig. 8), *jc4* opens the meter circuit, and at other contacts performs restoratory operations. The calling subscriber's meter and relay HS become released but, in the absence of negative on wire 30 *pc* (or *pf*), the cord does not yet become available.

Relay HS at its contacts.—*hs1* reconnects wire *ps* (extension of wire *pc*) to wire *kb*, *hs2* disconnects earth from wire *pf* and thus from relays HF and DF, and from wire *pt*, and reconnects 35 earth to wire *gc*, *hs6* reconnects negative to wire *gs* to render the secondary line finder available and at other contacts performs restoratory operations.

Relay HF at its contacts.—*hf2* reconnects negative 40 to wire *la* to render the primary line finder available, *hf5* removes earth from wire *ps* and thus from relays LS and KS of the calling subscriber's line, and at other contacts performs restoratory operations. Relays LS and KS of the 45 calling subscriber become released and the calling subscriber is thus enabled to initiate and receive further calls.

It will be noticed that everything is now made 50 available for further use except the cord circuit, but that the two supervisory lamps CS and CC are glowing. The operator, observing the two lamps, withdraws the plug from jack JM and restores it to its seat. Hereby contacts *ps* (Fig. 15) open the circuits of windings BT(II), FC(II), 55 and MC(II) of relays BT, FC, and MC and these relays become released.

Relays BT and FC at their contacts perform restoratory operations, and relay MC at its contacts: *mc4* opens the circuits of the supervisory 60 lamps, *mc5* reconnects negative to wire *pc* (or *pf*) to render the cord available for further use, and at its other contacts performs restoratory operation.

If the called subscriber had not replied, relays 65 DC and FC would not have become operated. With these conditions, as soon as the calling subscriber hung up his telephone, his line would have become released in an exactly similar manner to that described above except that the meter 70 circuit would have extended from earth, via contact *bt3*, *jc4*, *bc3*, *nc1*, and *fc4* to wire *mc*.

If the wanted subscriber's line had been already engaged there would have been earth on wire *pm* of jack *jm* and consequently there would 75

have been no circuit for windings MC(I) and NC(I) of relays MC and NC. On the other hand there would have been a circuit for winding MC(III) of relay MC. Relay MC would have performed its normal operations. Busy tone would have been connected to the calling line by way of contact *nc6* (at rest) and metering would have been prevented by contact *nc7*.

If the calling subscriber had asked for an unavailable number, that is for the number of a non-existent subscriber, the operator would have inserted the plug into jack NU (Fig. 14) and matters would have proceeded as for a correct call. The called supervisory lamp CS would have been caused to flash.

It will have been observed that a calling subscriber is entirely anonymous. It may have been observed also, that when restored to service, the primary and secondary line-finders and cord-seekers were not disturbed from the position they had occupied but were merely rendered available for fresh service. If they are taken into service again it is probable that their positions will be disturbed and the two line-finders which have been in association may not be associated for a succeeding call; thus all chance of identifying the previous caller will be lost. It may be, moreover, that the anonymity of the calling subscriber is maintained throughout the connection and yet the called subscriber may wish to destroy the anonymity of the caller. To this end it is arranged that if the called subscriber, who wishes to destroy the anonymity of a caller, does not hang up his telephone, the line-finders and cord-seekers are not rendered available for service but remain associated with the circuit with which they were last used. Thus, the cord-seeker (if one was used) will remain with its wipers in association with the contacts of the cord-circuit, the secondary line-finder (if one was used) will remain with its wipers in association with the contacts of the indirectly connected line-finder, and the primary line-finder (indirectly or directly connected as the case may have been) will remain with its wipers associated with the contacts of the calling subscriber who was responsible for their use and whose identity it is desired to discover, and moreover, these pieces of apparatus will be maintained in an unavailable state (no negative on wires *gs* and *la*) though the caller will be released and be able to initiate and receive calls.

The clearing operations under these conditions are as follows: As the called subscriber has not hung up his telephone, relay DC will not be released and lamp CS will not glow. Relay DC will maintain closed its contacts *dc3* and *dc4*.

When the calling subscriber hangs up his telephone, relay LC will become released.

60 *Relay LC at its contacts.*—*lc1* opens the circuit of relay BC, *lc2* closes the circuit of supervisory lamp CC, *lc3* closes a circuit for relay HA common to the operator's position, and *lc4* closes a circuit to wire *ch* (Fig. 8) and thence, via level and wiper CHC, contacts *ns6* and *hs8* to relay CH. The calling supervisory lamp glows and relays HA and CH become operated and, after a delay, relay BC becomes released.

70 *Relay HA at its contact.*—*ha1* closes a circuit for a distinctive signal, such as a coloured lamp CL, at the operator's position, and *ha2* may close a general alarm circuit.

75 *Relay CH (Fig. 8) at its contacts.*—*ch1* closes a holding circuit for itself, *ch2* closes a holding circuit for relay NS should such have been oper-

ated, *ch3* opens a point in the circuit of relay GS, so that, in spite of the eventual release of relay HS, negative will be withheld from wire *gs* and the secondary line-finder will be withheld from service, *ch4* closes a circuit for lamp CHL, and 5 *ch5* connects earth to wire *cf* (Fig. 7) and thus to wire *la* and winding DF(II) of relay DF. Relay DF is thus maintained operated in spite of the eventual release of relay HF and the earth on wire *la* maintains the indirectly connected line 10 finder in an unavailable state.

15 *Relay BC (Fig. 15) at its contacts.*—*bc1* removes one source of earth from wire *pc*, *bc2* opens the circuit of relay JC, and at other contacts performs other operations as before. Relay JC 15 becomes released.

20 *Relay JC at its contact.*—*jc1* removes earth from wire *pc* and thus from relay HS, and at its other contacts performs other operations as before. Relay HS becomes released.

25 *Relay HS at its contact.*—*hs2* removes earth from wire *pf* and thus from relay HF, and at its other contacts performs other operations as before. Relay HF becomes released.

30 *Relay HF at its contact.*—*hf2* reconnects negative to wire *la* (but this negative is short circuited by the earth from wire *cf*), *hf5* removes earth from wire *ps* and thus from relays LS and KS of the calling subscriber's line. Relays LS and KS become released and the calling subscriber is thus enabled to initiate or receive further calls.

35 (If an indirectly connected line-finder had not been employed, but, instead, a directly connected one had been employed, the earth placed upon wire *ch* would appear on wire *cf* with results similar to those described.)

40 The operator seeing lamp CL glow will easily be able to ascertain which cord has connected to it a called subscriber, who wishes to establish the identity of the subscriber who called him, by observing which cord has its calling supervisory lamp CC glowing and its called supervisory lamp CS darkened. The operator is able to have the connection traced by an observation of the 45 positions of the several switches, assisted by an observation of lamp CHL.

45 If, at the stage at which the calling subscriber has established communication with her, the operator wishes to hold up the connection, she may 50 do so by the operation of key HK, which, by maintaining earth on wire *pc*, holds relay HS (or HF) and thus relays LS and KS of the calling subscriber. Under these conditions not only 55 are the line-finders and cord rendered unavailable but also the calling subscriber's line is not released.

55 There now remains to describe the manner in which three so called "pips of tone" are counted, the manner in which they are made audible to 60 the calling subscriber and the manner in which the last "pip" is made audible to the operator.

65 It may be recalled that the sequence of operations which led to this effect was, relay LC brought about the operation of relay BC, relay BC brought about the operation of relay PC, relay PC brought about the operation of relay PF, and relay PF closed its contacts *pf6*. Relay UO therefore became operated.

70 *Relay UO at its contacts.*—*uo1* closes a circuit 70 for relay VO, and *uo2* prepares a first circuit for relay ZO. Relay VO becomes operated.

75 *Relay VO at its contacts.*—*vo1* closes a circuit for relay WO, and *vo2* opens a point in a second circuit of relay ZO. Relay WO becomes operated. 75

- Relay WO at its contacts.*—*wo1* closes a circuit for relay XO, and *wo2* prepares a point in the above named second circuit of relay ZO. Relay XO becomes operated.
- 6 *Relay XO at its contacts.*—*xo1* closes a circuit for relay YO, *xo2* opens a point in a third circuit of relay ZO, and *xo3* opens a point in the operator's receiver circuit. Relay YO becomes operated.
- 10 *Relay YO at its contacts.*—*yo1* completes the first circuit for relay ZO, *yo2* opens the circuit of relay UO, *yo3* and *yo4* connects the tone circuit *zt* to the cord circuit by way of condensers 1 and 2. Relay ZO becomes operated and relay UO becomes released after a short delay.
- 15 *Relay ZO at its contacts.*—*zo1* closes a holding circuit via contact *zo2*, *zo2* opens a further point in the circuit of relay UO, and *zo3* completes the tone circuit *zt*.
- 20 *Relay UO at its contacts.*—*uo1* opens the circuit of relay VO, and *uo2* opens the first circuit of relay ZO in which that relay is holding. Relay ZO becomes released and relay VO becomes released after a delay.
- 25 *Relay ZO at its contacts.*—*zo1* opens a point in the already opened holding circuit, *zo2* prepares a point in the circuit of relay UO, and *zo3* opens the tone circuit. Thus has been transmitted to the calling subscriber one "pip" of tone.
- 30 *Relay VO at its contacts.*—*vo1* opens the circuit of relay WO, and *vo2* closes the second circuit of relay ZO. Relay ZO becomes operated and relay WO, after a delay, becomes released.
- 35 *Relay ZO at its contacts.*—*zo1* and *zo2* performs operations of no present interest, and *zo3* completes the tone circuit *zt*.
- Relay WO at its contacts.*—*wo1* opens the circuit of relay XO, and *wo2* opens the second circuit of relay ZO. Relay ZO becomes released and relay XO becomes released after a delay.
- 40 *Relay ZO at its contact* *zo3* *opens the tone circuit.* Thus a second "pip" of tone has been transmitted to the calling subscriber.
- 45 *Relay XO at its contacts.*—*xo1* opens the circuit of relay YO, *xo2* closes the third circuit (via contact *xo1*) of relay ZO, and *xo3* closes the point in the operator's telephone circuit. Relay ZO becomes operated and relay YO after a delay becomes released.
- 50 *Relay ZO at its contacts.*—*zo1* closes a holding circuit (via contact *zo2*), *zo2* opens a point in the circuit of relay UO, and *zo3* completes the tone circuit *zt*.
- 55 *Relay YO at its contacts* *yo1* *opens the point in the third circuit of relay ZO* (but this relay has a holding circuit) *yo2* *closes a point in the circuit of relay UO* (but this circuit is open at contact *zo2*), and *yo3* and *yo4* *disconnects the tone circuit from the cord circuit.* Thus there has been transmitted to the calling subscriber a third and final "pip" of tone. This final "pip" was also transmitted, via contact *xo3* to the operator.
- 60 *The automatic cyclic operation of relays UO to ZO is now arrested by relay ZO which can be released only by the opening of contact p/f or of key RP.*
- 65 *If key RP be opened and then again closes, it can be seen that the cycle of operations of relays UO to ZO will be repeated. This indicates to the subscriber that he is required by the operator to repeat the number of the line to which he wishes his own line to be extended. (It may be observed that the operator has no microphone.)*
- 70 *In Fig. 8 there is shown a relay NS. During certain slack periods, such as at night, the circuit*
- of this relay is prepared, as by the closure of a key. When, under these conditions relay GS becomes operated it, at its contact *gs2*, completes the circuit of relay NS. Relay NS becomes operated.
- 75 *Relay NS at its contacts.*—*ns1* closes a holding circuit for itself by way of contact *hs1*, *ns2* to *ns5* effects wiper switching for the cord-seeker whereby the latter is caused to select a connecting circuit, such as that shown in Fig. 17, on a 10 night or concentration position.
- 80 *When the calling line becomes connected to the connecting circuit (Fig. 17) a circuit is completed over wiper *MN* (instead of wiper *MC*), wire *mn*, contact *co3* to winding *BN(I)* of relay BN and the subscriber's loop is extended over wipers *+N* and *-N* to relay LN. Relays BN and LN become operated.*
- 85 *Relay BN at its contacts.*—*bn1* prepares a holding circuit for winding *BN(II)* of relay BN, *bn2* switches out lamp CN (the calling lamp for a C subscriber) and switches in lamp AN, and *bn3* prepares the meter circuit.
- 90 *Relay LN at its contact* *ln1* *closes a circuit for relay BB.* Relay BB becomes operated.
- 95 *Relay BB at its contacts.*—*bb1* connects earth to wire *pn* to render the circuit unavailable to other cord-seekers and to hold relay HS, *bb2* closes the circuit for lamp AN, *bb3* opens a point in the meter circuit, and *bb4* prepares a circuit for relay JR. Lamp AN glows.
- 100 *The operator seeing lamp AN glowing will, by inserting a plug in jack JN, ascertain the requirements of the calling subscriber and will then extend the connection accordingly, all in accordance with established methods.*
- 105 *When a plug is inserted into jack JN a circuit is completed for relay CO. Relay CO becomes operated.*
- 110 *Relay CO at its contacts.*—*co1* opens the circuit of lamp AN and closes the circuit for winding *BN(II)* of relay BN, *co2* removes negative from wire *pn*, and *co3* disconnects winding *BN(I)* of relay BN and prepares a further point in the meter circuit.
- 115 *When the called subscriber replies, circuit changes take place in the cord-circuit (not shown) used by the operator which result in earth being connected to the "sleeve" of jack JN. Relay JR becomes operated.*
- 120 *Relay JR at its contacts.*—*jr1* connects another source of earth to wire *pn*, *jr2* closes a further point in the meter circuit, which is now open only at contact *bb3*, and *jr3* connects an alternative source of earth to relay CO in order that the release of that relay may be delayed somewhat after the withdrawal of the plug.
- 125 *When the calling subscriber hangs up, relays LN, BB and JR, in that order, become released. Relays BB and JR remove earth from wire PN whereby, in the manner described in connection with Fig. 15, the calling subscriber's line is freed, and, in the interval between the release of the two relays contacts *bb3* and *jr2* effect metering.*
- 130 *As long as the called subscriber does not hang up, the operator will not withdraw the plug from jack JN. Hereby relay CO will be held operated. With relay CO operated and relay LN released, a circuit will be completed via wire *cn* to relay CH with effects as in the previous example.*
- 135 *We claim:*
- 140 *1. In a telephone system, means including a plurality of serially related automatic switches including both backward and forward selecting switches operated to establish a connection be-*

tween the calling and the called line, means enabling the calling party to release his line from the connection and make another call, and means for maintaining all of said switches in their antecedent operated position and for guarding them against intrusion by other calls until the called party hangs up.

2. In a telephone system, means including a plurality of serially related automatic switches for setting up a connection from the calling line to a called line, one of said switches being a finder switch having an allotter associated therewith for assigning the finder for use, means whereby the calling party can release his line from the connection and make another call, and means whereby the called party by failing to hang up his receiver can maintain the automatic switches used in said connection in their respective operated

positions and prevent the allotter from reassigning said finder for use so that the connection can be traced back to the calling line.

3. In a telephone system, means including a plurality of serially related automatic switches for setting up a connection from a calling to a called line said means also including a manual switchboard, means whereby the calling party can release his line from the connection and make another call, and means whereby the called party or the operator at said manual switchboard can maintain the automatic switches used for the connection in their respective operated positions so that the connection can be traced to the calling line.

WILLIAM GEORGE PATTERSON.
REGINALD GRIFFITH DIXON.
